UNITED STATES PATENT OFFICE

115,301

DESIGN FOR A WRENCH

August Gus Spexarth, Astoria, Oreg.

Application April 3, 1939, Serial No. 84,001

Term of patent 3½ years

To all whom it may concern:

Be it known that I, August Gus Spexarth, a citizen of the United States of America, residing at Astoria, in the county of Clatsop and State of Oregon, have invented a new, original, and ornamental Design for a Wrench, of which the following is a specification, reference being had to the accompanying drawing, forming a part thereof.

Fig. 1 is a top plan view of a wrench, showing my new design;

Fig. 2 is a side elevation thereof;
Fig. 3 is a bottom plan view thereof; and
Fig. 4 is an enlarged longitudinal section taken on the line 4—4 of Fig. 1.

I claim:

The ornamental design for a wrench, substantially as shown.

AUGUST GUS SPEXARTH.
